17 Claims. (Cl. 101—93)

This invention relates to printing mechanisms adapted to print characters such as numerals, alphabetical characters, etc., upon a record sheet.

5 The main object of the present invention is to devise a printing mechanism which is especially adapted for performing printing operations at high speeds. In carrying out this main object of the invention printing type are carried by a wheel which is rotatable and is in continuous rotation. When the preselected type is at the printing line an impression is taken from the type without interrupting the rotation of the wheel or the driver that effects its rotation.

10 Another object of the present invention is to devise a printing mechanism for printing alphabetical characters and numerals utilizing a conventional platen and avoiding the use of type hammers. The use of a conventional platen is of great importance and advantage since it permits a more satisfactory means for carrying a sheet to be printed and for feeding the sheet in line space or variable spacing operations.

15 Another object of the present invention is to provide an improved arrangement for taking an impression from a selected type onto the platen without stopping the rotation of the wheel carrying the type but, nevertheless, taking the impression when the type is stationary. This apparent inconsistency is effected by causing the printing wheel to be rotated in one direction and then causing the printing wheel to roll over its operating gear in the opposite direction as the printing wheel is rocked toward the platen.

20 so that the selected type is stationary when it strikes the platen. By this arrangement the printing wheels operate as type hammers and impressions are effected while type are stationary without interrupting the rotation of the printing wheel or its driver, and the use of a conventional platen is permitted.

25 Another object of the present invention is to arrange the type elements in the printing wheel in groups, therein being one group of numeral type and three groups of alphabetical characters, and to provide means under control of a selecting means to select the desired group of type and select the desired type of the selected group.

30 This is attained by analyzing a perforated card to select a type in the four different groups and then selecting the desired group by the analyzing of special holes in the same card.

35 Another object of the present invention is to cause group and type selection to be effected in the same analyzing cycle of the same card.

40 The numeral type 1-9 are selected by perforations 1-9 and at a desired point in the operating cycle an impression is effected from the selected type. Alphabetical characters are selected by

effecting an impression at points in the cycle earlier than the printing impression is effected from the numeral type, and the points in the cycle are selected under control of the special holes. This arrangement is also a broad object 5 of the present invention as it provides a numeral and alphabetical type printing mechanism operating for printing impressions in different points in the cycle. This division results in a smoother operating cycle since hammer blows are effected at four different points in the cycle instead of a single point. The shocks to the machine effected by the hammer blows are thereby distributed and are less in intensity so that the parts to which shocks and strains 10 are distributed can be less rugged in size thus cheapening the cost of manufacture and diminishing the service requirements.

Further objects of the instant invention reside in any novel feature of construction or operation or novel combination of parts present in the embodiment of the invention described and shown in the accompanying drawings whether within or without the scope of the appended claims and irrespective of other specific 20 statements as to the scope of the invention contained herein.

In the drawings:

Fig. 1 is a view in side elevation of one order of the improved numeral and alphabet printing 30 mechanism.

Fig. 1a is a diagram illustrating the code for the selection of numeral and alphabet printing characters.

Fig. 2 is a view in side elevation showing in a 35 diagrammatic manner the essential elements of a well known form of tabulating machine to understand more clearly the operation of the improved printing mechanism.

Fig. 3 is a view in front elevation and is taken 40 on the irregular section line 3—3 of Fig. 1.

Fig. 4 is a sectional view taken on the line 4—4 of Fig. 3 and shows particularly the speed varying mechanism.

Fig. 5 is a timing diagram of the machine. 45 The machine in which the present improvements have been incorporated is well known and is exemplified in the patents to Lake No. 1,379,268, dated May 24, 1921, Lake No. 1,600,413, dated September 21, 1926, and the patent to Daly et al. No. 1,896,540, dated February 7, 1933. 50

In machines illustrated in detail in the above described patents and generally herein, tabulating cards 10 (Fig. 2) are adapted to be fed singly or by a picker 11 from a supply stack to a pair of upper feeding rollers 12 which convey the card so as to have the perforations of the card analyzed by the usual perforation analyzing brushes 13, while the card is in motion. The card analyzed then passes to a lower set of feed- 60

ing rollers 14 which then convey the card to a storage hopper, usual in the type of machine referred to.

Card feeding operations are instituted by the usual manual start key designated as ST in the last mentioned patent so as to cause by an electrical circuit the energization of a card feed clutch magnet 15.

The power for driving the card feeding rollers 10 and other parts of the machine is derived from a motor (not shown) which by a belt 16 and pulley 17 constantly rotates a ratchet wheel 19 secured thereto. The pulley 17 and ratchet wheel 19 are loosely mounted upon a shaft 18.

15 In Fig. 2 there is shown the card feed clutch for causing card feed and is similar to the card feed clutch disclosed in Fig. 1a of the Lake Patent No. 1,822,594, dated September 8, 1931, to which reference should be had for details of construction 20 and operation.

Upon completion of the electrical circuit to clutch magnet 15, the latter attracts its armature 20 to raise a clutch lever 21 to thereby unlatch the latter from a clutch pawl 22. The latter is then drawn by a related spring 23 to engage the constantly rotating ratchet wheel 19. The clutch pawl 22 is carried by a bar 25, which is secured to a disk 26 secured to shaft 18 and to the latter there is secured a pinion 27.

25 The construction and operation of the card feed clutch, as is well known, are such that upon energization of magnet 15, disk 26 will be rotated and successive rotations of the shaft 18, and therefore pinion 27, will ensue as long as tabulating operations are desired.

30 The pinion 27 is in mesh with a gear 28 and the latter drives the upper set of feeding rollers 12 and the lower set of feeding rollers 14. The upper set of feeding rollers is intergeared by pinions 29, 35 one of which is rotatable with a gear 30 in mesh with the driving gear 28. The latter also meshes with a pinion 31 which is rotatable with one of a pair of intergeared pinions 32 carried by the rollers 14 which drive the lower set of feeding 40 rollers 14 in opposite directions. The driving gear 28 is of sufficient width to drive a gear 34 so that by a train of gears 35, 36 a shaft 37 is driven. It is understood that as is usual in tabulating machines the card feed clutch is so designed and 45 the gears are so proportioned that shaft 37 will be given a complete revolution in the arrow direction shown in Fig. 2.

50 It is customary in the type of machine described to cause printing from numeral type of a printing mechanism which are presented to a printing line and which are selected in accordance with the analyzing of the perforations of the card, and to carry out the printing function in a novel manner an improved construction will now be described.

Numeral printing mechanism

55 As best shown in Fig. 4, to the shaft 37 which rotates one revolution for each card cycle there is secured a gear 38 which through a speed reduction mechanism, to be hereinafter described, drives a pinion 39 attached to a clutch shaft 40, the driving connection being such that shaft 40 will be driven two revolutions for each revolution of shaft 37.

60 Shaft 40 fixedly carries a notched clutch disk 41 (Fig. 1) and adjacent the clutch disk 41 there is loosely mounted gear 42 to which is pivotally mounted a spring urged clutch pawl 43, the latter being normally engaged by a clutch release arm

44 so as to hold the clutch tooth 45 out of engagement with a clutch notch of the clutch disk 41.

The above described clutch is the printing type selecting clutch and causes the differential rotation of a printing wheel 48. To rotate the type wheel 48, the gear 42 meshes with an idler gear 46 loosely mounted on a shaft 47 and the gear 46 meshes with the type carrying wheel or gear 48 carrying the digit printing type 0-9 inclusive and comprising the numeral type group, the numeral type being spaced four teeth apart.

Fig. 1 shows the arrangement of the printing devices for a single order and the machine is preferably provided with duplicate devices for printing the digits of different denominational orders.

The card is perforated with holes to represent the digits 0-9 and is passed by the analyzing brushes 13 to analyze the index points in the order 9, 8, 7, . . . 0.

When the analyzing brush 13 senses a hole, a circuit is closed to a printing control magnet 49 (Fig. 2) and for each card column analyzed, there is a printing control magnet 49. When a printing control magnet 49 is energized, its armature 50 (Fig. 1) is attracted so as to pull a call wire 51 to the right. The latter has a head portion comprising extensions 52 and 53, the extension 52 normally engaging a lug of an arm 54 which is the integral depending part of the clutch release arm 44. The normal engagement of extension 52 and lug 53 is retained during the time the holes 9, 8, 7, 6, 5, 4, 3, 2, and 1 are analyzed to thereby cause the clutch release arm 44 to be rocked. The clutch pawl 43 is now rocked by its spring to cause its tooth 45 to engage a particular notch of the clutch disk 41 to thereby cause the gear 42 to be rotated and through the idler gear 46 rotate the printing gear wheel 48.

If the "9" or first hole was analyzed, the clutch disk 41 would rotate the extent of one notch before the clutch engagement is effected by the energization of the magnet 49. The printing wheel 48 will thereafter rotate so as to bring the "9" numeral type to the printing line.

In the above manner the printing type wheels are picked up at differential times so that at a predetermined point in the cycle of machine operation the printing wheels will represent at the printing line the selected digits, it being noted that the "0" type is normally at the printing line so that no movement of a printing wheel is necessary to select "0" for printing.

From Figs. 1 and 3, it will be seen that the free ends of the call wires 51 pass between a rod 55 and a bar 56 of a bail shaped frame which is pivoted at 57. One side arm of the bail shaped frame has a depending follower arm 58 carrying a roller 59 coacting with a cam 60 secured to the shaft 37.

After the "1" index point is analyzed, the "0" hole is sensed by the analyzing brush if it is present but before analyzing the "0" hole, an inclined cam edge 60a (Fig. 1) of a high portion of cam 60 acting on the follower arm 58 rocks the bail shaped frame clockwise causing the rod 55 and bar 56 to depress all the free ends of the call wires 51 so as to disengage the extensions 52 from the lugs of arms 54. Obviously, with this relationship even though a magnet 49 is energized by the presence of a "0" hole, the printing type selecting clutch for rotating the printing wheel will not be engaged so that, when the printing impression is effected, the "0" digit will be printed.

Each printing wheel is carried by an arm 61 loosely pivoted on the shaft 47 and is provided

with follower arms 62, each of which engages a related cam of a pair of complementary cams 63.

Referring to Fig. 4, attached to the shaft 37 is a gear 65 driving a pinion 66 attached to a shaft

67. There is a printing clutch for each printing wheel for causing the impression to be effected and is similar to the previously described printing type selecting clutch and comprises the clutch disk 64, a clutch pawl 68 carried by one of the 10 complementary cams 63 and a clutch release arm 69 having an integral depending arm 70.

For each printing wheel that is set to any digit from "1" to "9", a cam 71 attached to a related gear 46 will rock a double arm 72. One end of each arm 72 carries a pin 74 engaging a slot 75 of a link 76, the latter being pivoted at 77 to an interposer 78, a series of the interposers 78 being pivoted on a rod 79. Obviously, when the double arm 72 is rocked by the cam 71, the link 76 is depressed to rock the related interposer 78 to bring its free or right end in front of a lug 80 of the arm 70.

The interposers 78 are carried, as stated, by the rod 79 and the latter is carried by a pair of depending arms 81, one of which is provided with a projection 82 coacting with a profile cam 83 secured to the shaft 37.

After all the index points of the card which comprises the index points 0-9 and the special index points X and R have been analyzed, the projection 82 will drop from the high part of the cam 83 to a low part 83a permitting a spring 84 attached to an arm 81 to shift all the interposers 78 to the right and those that have been 35 rocked by the depression of a related link 76 will by their shifting rock the arms 80 and, therefore, the clutch release arms 69, causing the clutch engagement so that complementary cams 63 will now rotate to rock all the arms 61 to force 40 the printing wheels 48 against the usual inking ribbon and platen 85 around which is fed a paper to be imprinted.

As each arm 61 is rocked, the printing wheel is rotated counterclockwise but, since the printing wheel is rolling over the gear 46, this rolling action will cause an equal and simultaneous rotation in a clockwise direction. Both of these opposite rotations will, in effect, cause the printing wheel 48 to be substantially stationary when 55 it strikes the platen 85, the type striking the latter squarely and firmly to cause a legible impression.

After the index points 9-1 have been analyzed, it is desirable to positively retract all of the attracted armatures 50 in the event that residual magnetism causes them to remain attracted to the cores, so that they may again be attracted, preferably for a purpose to be later understood in connection with alphabet type selection.

To this end each call wire 51 has an extension 50 cooperating with a bail 91, the latter being normally positioned so as to permit the call wire 51 to be freely shifted to the right when a magnet 49 is energized.

The bail shaped frame 91 is pivoted at 92 and has a depending arm 93 having an extension 94 cooperating with a cam 95. After analyzing the "1" index point, a high portion 95a of cam 95 engages the extension 94 and thus rocks bail 91 to the left to retract all the call wires, if they have not been retracted. This operation occurs just slightly before the call wires 51 are depressed by the rod 55 and bar 56.

After the printing operation, since the clutch 75 is still engaged, the printing wheels continue to

rotate until the clutch pawl 43 strikes the clutch release arm 44 thereby disengaging the clutch and which is effected when the printing wheels are at "0".

The clutch which causes the rotation of the 5 cams 63 to effect the imprint continues its engagement for a complete rotation of the cams 63 and the clutch disengagement is effected by the engagement of the clutch pawl 68 with the arm 69.

Zero insertion

In printing a multi-denominational number as 3.00 it is necessary to insert the zeros to the right of "3". This is effected by the usual coupling 15 levers 86, each of which is pivoted on the link 76 and has a lug 87 engaging a lug 88 of a pitman next lower in order so as to rock the interposer lower in order if the related printing wheel has not been set, to thus cause "0" printing.

By adjusting the coupling levers to disengage the lugs 87 and 88, the printing mechanism may be split at desired points, as is well known in the art.

Alphabet printing mechanism

The machine is preferably provided with alphabet character printing type and means for selecting such type so as to print, aside from numerals, letters making up words or abbreviations.

The alphabet type are selected according to 30 groups, the code being shown in Fig. 1a. The particular group selected determines which of the several type related to an index point will be printed. For example, if the perforation should be the "2" hole, and no pilot hole is utilized in 35 either the "O", "X" or "R" positions "2" will be printed. If a hole is also at "O", the "O" hole will select the type "S". If at the "X" index point position type "K" will be selected, and if at the "R" index point position type "B" will be selected. 10

To more clearly understand the principle of operation, it should be noted that from the timing diagram of cam 83 the selected numeral type have their impressions taken therefrom after all the index points have been analyzed and, of 45 course, is after the "R" index point has been analyzed. The alphabet type selection is provided for by taking the printing impression before the time a numeral type would have been printed and this is effected under control of the 50 index points "O", "X" and "R".

If the hole was at the "9" index position alone, the printing wheel 48 would rotate counterclockwise until "9" was at the printing line and then the printing wheel carrying arm 61 would be 55 rocked to effect the imprint. It will be noted that, if a perforation was at the "R" position and then under control of this perforation, the printing impression clutch 64-68 was engaged, the printing wheel 48 will be rocked earlier than for 60 printing a numeral "9" to take an imprint from the "I" type. The perforation at the "X" position will take an imprint still earlier to print "R" and the perforation at the "O" position still earlier than to print "R" to print "Z".

The same principle of operation is provided for selecting the other alphabet type.

It will be recalled that, after the "1" perforation is analyzed, bail 91 positively retracts the attracted armatures 50 and thereafter members 55 70 and 56 are depressed so as to cause the call wires 51 to be disengaged from the arms 54 and to cause the extensions 53 of the call wires to be placed in front of the lugs 80 of the arms 70. Obviously, the energization of a magnet 49 will, 75

after the "1" perforation is analyzed, cause the arm 70 to be rocked and the clutch release arm 69 to be rocked, and at a time depending upon the pilot hole analyzed. Hence, the type printing clutch 64—68 will be released to cause the printing impression from the selected type.

It is pointed out that for alphabet type printing, impressions are made at three different points in the operation cycle or after the "O", "X" and "R" perforations are analyzed, whereas for numeral printing the impressions are made only after all the perforations are analyzed and at a single point in the operating cycle.

Attention is directed to Fig. 4 which discloses a speed reduction mechanism for shaft 40, the shaft 67 being rotated at a constant speed by the gear 65 driven by shaft 37.

This speed reduction mechanism comprises an arm 96 pivoted by a stud 97 on the gear 65 and thereby said arm 96 is given a clockwise rotation of one revolution for each card cycle. The arm 96 carries a roller 98 engaging the cam race of a box cam 99 (Fig. 3) fixed to a side frame by screws 100. The gear 38 is loosely mounted on the shaft 37 and carries a stud 101 forming the pivotal point of a block 102 engaged by forked extensions 103 of arm 96.

The arm 96 is varied in its angular position with respect to the gear 65 by the configuration 30 of the cam race of the box cam 99 so that in the clockwise rotation of the gear 65 the arm 96 is rocked so that its free end is moved towards the shaft 37, thus causing the gear 38 to back up with relation to the gear 65 thus causing the gear 38 to 35 fall behind the gear 65 and reducing its speed.

The cam race portion 104 of the box cam has a configuration which effects a driving of the gear 38 at the same speed as the gear 65 so that during the analyzing of the index points 9-2, the 40 gears 65 and 38 rotate at the same speed, each gear rotating 18° per index point, or a distance equivalent to four teeth of the type wheel. Thereafter, at about the cam portion 105 the arm 96 is rocked towards the shaft 37 rocking 45 the gear 38 backwardly with respect to the gear 65, thus reducing the speed of the gear 38. Thereafter, the cam portion 106 rocks the arm 96 still further towards shaft 37 but in such a manner as to render the speed of gear 38 constant 50 and equal to one quarter of the speed of gear 65, during which time the selected numeral or alphabet type are printed from. The final cam portion 107 increases the speed of gear 38 so that during the final part of the cycle, the gear 38 is 55 finally restored to the normal relation with respect to gear 65.

The purpose of the speed reduction which causes by the cam portion 103 the gear 38 to rotate one quarter the speed of gear 65 is to select for printing a particular type within the 60 group of type related to the same index point. The printing operation for alphabet type is effected by the engagement of clutch 64—68 when the index points "O", "X" and "R" are analyzed, 65 these index points having the same spacing as the index points 9-1. However, to keep the printing wheel 48 small in diameter, the alphabet type are arranged closely so that to select these type the printing wheel must rotate at a reduced speed 70 as the index points "O", "X" and "R" are analyzed.

For a more concrete illustration take, for example, the selection for printing of the alphabet type "X" selected by the two holes "7" and "O".

When the "7" hole is sensed, the printing wheel

starts to turn at about 54° and, if it should rotate at a constant speed, the printing wheel would have rotated 30 teeth at the time "O" hole was analyzed to cause the printing and at this time the printing wheel would have been in such a 5 position to print "Q" instead of "X". If the pilot hole was the "X" hole, an "R" would be printed instead of "P" and, if the pilot hole was the "R" hole, a blank would be printed instead of "G". Without the speed reduction at the numerical 10 printing time for printing "7" the clutch 41—45 would have been latched up so that a "O" would be printed. Therefore, such constant speed cannot be named and the speed reducing mechanism is preferably utilized to cause the printing from 15 the desired type.

It should also be noted from the timing diagram that the type wheel rotates at a reduced speed for numeral printing irrespective of the 20 numeral type selected and also for the selection 20 of the alphabet type at the printing time. The complementary cams 63 are so designed as to rock the arms 61 to roll the printing wheels over the gears 46 at the same speed as the printing 25 wheel is being rotated at its reduced speed, but 25 opposite in direction so that the numeral or alphabet type are substantially stationary when an impression is effected therefrom.

While there has been shown and described and pointed out the fundamental novel features of 30 the invention as applied to a single modification, it will be understood that various omissions and substitutions and changes in the form and details of the device illustrated and in its operation may be made by those skilled in the art without departing from the spirit of the invention. It is the intention therefore to be limited only as indicated by the scope of the following claims.

What is claimed is:

1. In a printing machine, in combination, a rotatable numeral wheel carrying interspersed alphabet and numeral type divided into a group of 40 numeral type and several groups of alphabet type, means for rotating said wheel, means for effecting an impression from the type on said 45 wheel, means for effecting a predetermined extent of rotation of said wheel from its rest position in each machine operation by said rotating means for selecting a group of type and means for selecting a type in the selected group comprising means controlled by said type selecting means for causing the operation of said impression effecting means at predetermined points in the cycle of machine operation and commensurate in number with the number of type in a 55 group.

2. In a printing machine, a rotatable wheel carrying several groups of type, comprising groups of alphabet type and a group of numeral type, each type of which is presented to a printing line by a single rotation of said wheel, means for selecting one of the groups of alphabet type or said numeral type, means for selecting the alphabet type within the selected group, means for taking an impression from the selected type, means rendered effective by said alphabet type selecting means for causing the operation of the impression effecting means at different points in the cycle of machine operation, and means 60 whereby in order to select any of said numeral type of the group of numeral type for printing during one single revolution of the printing wheel the impression taking means is operated at a 65 predetermined point in the revolution of said 70 wheel.

printing wheel and which point is common for printing all of said numerals.

3. The combination with a movable member carrying several groups of type for presenting type of said groups of type to a printing line, means for moving said member, a platen, means for rocking said member against said platen for a printing impression, means including a clutch intermediate said moving means and said member to move the latter for selecting a group of type, control means for selecting a type in the selected group of type, a clutch intermediate said moving means and said rocking means which is engaged for causing the operation of said rocking means, and means controlled by said type group selecting control means for causing the engagement of said last-named clutch at the time the type of the selected group of type is at the printing line.

20 4. The combination with a movable member carrying several groups of type for presenting said type to a printing line, control means for selecting a group of type, means for effecting printing impressions from said type, operating means for the latter, control means for selecting a type in the selected group of type, a clutch intermediate said operating means and said impression effecting means which is engaged for causing the operation of said means for effecting printing impressions, and means controlled by said type group selecting control means for causing the engagement of said clutch at the time the selected type of the selected group is at the printing line.

35 5. In a card controlled machine, a member carrying a plurality of groups of type comprising for each group a plurality of alphabet type, an electro-magnet, means for analyzing the holes 1-9 and then O, X and R of the same card to cause a double energization of said electromagnet, means for moving said member for presenting the type of said groups of type to a printing line when said holes 1-9 are being analyzed, impression effecting means, a call wire operated by the energization of said electromagnet and normally controlling the operation of said moving means to select a group of type in accordance with the holes 1-9 being analyzed, means for disabling the control of said call wire of the operation of said moving means and effecting an operative connection of said call wire and said impression effecting means, and means to cause the operation of the impression effecting means when the O, X and R holes are being analyzed and under control of said analyzing means to effect an impression from any type of the selected group.

60 6. The combination with a member movable to effect impressions from type carried thereby and rotatable to present the type carried thereby to a printing line, a driving means, a plurality of clutches, means rendered operative by the engagement of one of said clutches to cause the rotation of said member to present each type of a plurality of type to the printing line, means rendered operative by the engagement of the other of said clutches to effect the movement of said member to effect an impression from a selected type of the selected plurality, type group selecting control means, type selecting control means, and means controlled by each of said control means for effecting the engagement of the related clutch to cause the operation of the related means.

75 7. In a machine of the class described, the

combination with a rotatable member carrying type, means for rotating said member to present said type to a printing line, means for rocking said member to effect a printing impression from the type, a driving means, a plurality of clutches one of which engages said driving means with said rotating means and the other of which engages said driving means with said rocking means, selecting control means for selecting a plurality of type, means controlled by said selecting control means for causing the engagement of the first-named clutch for causing the rotation of said member to present each type of a selected plurality of type to the printing line, type selecting control means, and means controlled by said type selecting control means to cause said other clutch to be engaged to effect the operation of said rocking means to cause the impression from a desired type of the selected plurality.

8. The combination with a rotatable means carrying a plurality of groups of type, the type being presented to a printing line while said means is in uninterrupted rotation in one direction, means for supporting said rotatable means to effect an impression from a selected type by rocking said supporting means, and means for rocking said supporting means and for causing by the rocking of said supporting means a relative reverse rotation of said rotatable means to thereby cause said type to be stationary during the printing impression.

9. In a card controlled machine of the class described, the combination with a wheel carrying type comprising numeral and alphabet type and rotatable to present said type to a printing line, of means for rotating said wheel, means for effecting an impression from a selected type, type selecting means cooperating with the digit representing holes of the card 1-9 for controlling said means for rotating said wheel for selecting a numeral type and a plurality of alphabet type, means for causing the operation of said impression effecting means at a predetermined point in the cycle of machine operation to effect a printing impression from any one of the selected numeral type, and a supplemental selecting means operative in response to the holes O, X and R of said card for causing in the absence of the operation of the preceding means the operation of the impression effecting means at other points in the cycle of machine operation to cause a printing impression of a selected alphabet type of the selected plurality of type.

10. A card controlled printing machine comprising, means for analyzing the holes in a card in the sequence 1-9, O, X and R, a printing wheel carrying numeral type and alphabet type, means for rotating said wheel, means for effecting an impression from the type on said wheel without stopping the rotation of said wheel, selecting means controlled by said analyzing means and operative when said holes 1-9 are analyzed to effect the rotation of said wheel a predetermined amount to select type comprising one numeral type and a plurality of alphabet type, means operative at a predetermined point in the cycle of machine operation which is common for printing from any numeral type to cause the operation of said impression effecting means to take an impression from any selected numeral type, and means controlled by said analyzing means and operative in the absence of the operation of the preceding means and under control of the holes O, X and R to cause the operation of the

- impression effecting means to take an impression from any one of the selected alphabet type.
11. In a card controlled machine, a driving means, a plurality of clutches, a rotatable wheel carrying type comprising numeral type interspersed with alphabet type, means operative by the engagement of one of said clutches with the driving means to cause the rotation of said wheel to select a plurality of type, means operative by the engagement of the other of said clutches with the driving means to effect the printing impression, type selecting means controlled by the holes 1-9 for causing the engagement of the first-named clutch to select a plurality of type comprising a numeral type and a plurality of alphabet type, alphabet type selecting means controlled by the holes O, X and R for causing the selection of the type of the selected plurality of alphabet type and the engagement of said other clutch, and means separate from said alphabet type selecting means and operable in the absence of the alphabet type selection for causing the engagement of said other clutch to effect an impression from any of the numeral type of the selected plurality of type.
12. In a card controlled printing machine, in combination, a member carrying several groups of type comprising numeral type interspersed with alphabet type, means for rotating said member a complete revolution to present any one of said type to a printing line, means for effecting an impression from said type, type selecting means controlling said rotating means and cooperating with the holes 1-9 of said card and type group means cooperating with the holes O, X and R of said card, means controlled by said type group selecting means for causing the operation of said impression effecting means coincident with the analyzing of the holes O, X and R to take an impression from a selected alphabet type, and means separate from said last-named means and operative in the absence of holes O, X and R to cause the operation of said impression effecting means to take an impression from any one of the selected numeral type.
13. In a card controlled machine the combination with a wheel carrying several groups of type comprising certain type and alphabet type, of means for effecting impressions from the type on said wheel, means for rotating said wheel to present the type to a printing line, type group selecting means controlling said impression effecting means, type selecting means controlling said rotating means, means cooperating with the lower holes of a card for controlling said type selecting means whereby the latter causes said rotating means to present a selected type to the printing line, means cooperating with the upper holes of the card for causing coincidentally with the analyzing of the upper holes the operation of said type group selecting means and said impression effecting means to thereby effect an impression from a selected type of the selected group of type, and means operating separately from said last-named means for causing the operation of said impression effecting means to take an impression from any of said certain type on said wheel when said upper holes are not present in the card.
14. In a card controlled machine the combination with a wheel carrying several groups of type comprising certain type and alphabet type, of means for effecting impressions from the type on said wheel, means for rotating said wheel to present the type to a printing line, type group selecting means controlling said impression effecting means, type selecting means controlling said rotating means, means cooperating with the lower holes of a card for controlling said type selecting means whereby the latter causes said rotating means to present a selected type to the printing line, means cooperating with the upper holes of the card for causing coincidentally with the analyzing of the upper holes the operation of said type group selecting means and said impression effecting means to thereby effect an impression from a selected type of the selected group of type, means for causing the operation of said impression effecting means to take an impression from said certain type on said wheel when said upper holes are not present in the card.
15. A rotatable member carrying a plurality of sets of type, means for selecting a set of type, rotating means for said member, means controlled by said selecting means for causing said rotating means to rotate said member a differential extent to select a set of type, type selecting means, and means for causing said rotating means to rotate said member at a reduced speed when said type are being selected.
16. In a card controlled machine, means for analyzing the equally spaced holes 1-9 of a card, then the correspondingly spaced O, X and R holes, a movable member carrying several sets of type, one set for each of the holes 1-9, means controlled by said analyzing means to cause said member to be moved at one speed to select a selected set of type when said holes 1-9 are being analyzed, and means for moving said member at a reduced speed when said holes O, X and R are being analyzed by said analyzing means to select a type in accordance with the holes O, X and R within the selected set.
17. In combination with a member movable to present all type of several groups of printing type to a printing line, means for uninterruptedly moving said member, a printing control magnet, means for analyzing card perforations to effect the energization of said magnet, means controlled by said magnet for effecting the movement of said member by said moving means at predetermined times in the movement of the latter to select a group of type, means rendered effective by a subsequent energization of said printing control magnet for effecting an impression from a selected type of the selected group during the uninterrupted movement of said member and while said type are passing through printing position, means controlled by said analyzing means upon analyzing other card perforations to effect a subsequent energization of said magnet, and means for automatically shifting the control of said magnet from the means for effecting the movement of said member to said impression effecting means.
